CLAIM

The ornamental design for a disinfectant wipes canister, as
shown and described.

DESCRIPTION

FIG. 1 is a perspective view of a new and ornamental design
for a disinfectant wipes canister;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

The broken lines shown represent portions of the disinfectant
wipes canister that form no part of the claimed design.
